UNITED STATES PATENT OFFICE.

MOLLIE L. GROSSMAN, OF NEW YORK, N. Y.

DESIGN FOR A HOLDER FOR NECKTIES.

56,870.

Specification for Design.

Patented Jan. 4, 1921.

Application filed July 31, 1918. Serial No. 247,680. Term of patent 7 years.

To all whom it may concern:

Be it known that I, MOLLIE L. GROSSMAN, a citizen of the United States, residing at New York city, in the county and State of New York, have invented a new, original, and ornamental design for a holder for neckties of the character worn by men and intended to contain the reserve stock of neckties and to be placed in or on a chiffonier or elsewhere or in a dress-suit case when it is desired to carry the ties therein, of which the following is a specification, reference being had to the accompanying drawings, forming a part thereof, and in which—

Figure 1 is a perspective view, and

Fig. 2 an edge elevation of a holder embodying my design.

I claim:

The ornamental design for a holder for neckties, as shown.

MOLLIE L. GROSSMAN.
